UNITED STATES PATENT OFFICE.

WARREN JOHNSON, OF NEW ORLEANS, LOUISIANA.

PAVEMENT.

1,253,600.

Specification of Letters Patent. Patented Jan. 15, 1913.

Application filed May 21, 1917. Serial No. 170,055.

To all whom it may concern:

Be it known that I, WARREN JOHNSON, a citizen of the United States, and a resident of New Orleans, in the parish of Orleans 5 and State of Louisiana, have invented new and useful Improvements in Pavements, of which the following is a specification.

My invention is an improvement in pavements, and has for an object to provide a 10 pavement composed of slabs of cement or concrete, having interlocking tongues and grooves, and having openings through which grouting may be poured after the slabs are laid to provide points of support for the 15 slabs.

In the drawings:

Figure 1 is a plan view of the improved pavement;

Fig. 2 is a vertical section;

Fig. 3 is a perspective view of one of the slabs;

Fig. 4 is a sectional view showing the edge of the pavement;

Fig. 5 is a perspective view of one corner 25 of a modified form of slab.

In the present embodiment of the invention, the pavement is composed of a series of slabs 1, each of which is provided at one side edge with a depending rib 2, having 30 a longitudinally extending groove 3 on its outer face, and at the opposite side edge each slab has a tongue 4 shaped to fit the groove of the adjacent block. This tongue, as shown, is rounded as is also the groove, 35 and it will be evident that by prying up a pair of slabs at the tongue and groove edge the slabs may be separated without rupturing the tongue or the rib. Each slab is also provided with a series of openings 5 for permitting the passage of grouting after the 40 slabs have been laid, and each block is also reinforced by a sheet of wire mesh 6, the said sheet being at the center of the slab, and it will be noticed upon inspection of 45 Fig. 2 that the sheet extends into the rib 2 and the tongue 4.

In laying the improved pavement, the surface of the ground is leveled as indicated at 7, and stakes 8 are set, the said stakes 50 having their tops at the pavement level. The slabs are laid on the stakes, the tongues being engaged with the grooves, after which grouting is poured down through the openings 5, as shown in Fig. 2, and the said 55 grouting will spread, forming a firm support for the slabs. It will be noticed that

there is a row of openings 5 at each edge of the slab and one across the center. At the edges of the pavement, the outermost slabs 1^a, instead of having grooves or ribs at their outer edges, have a depending portion 9, and the grouting poured through the openings 5 at this point will fill in the space on the inner side of the depending rib 9, thus making a smooth, neat finish at this 65 point.

In Fig. 5 the slab 10 has the ribs 11 corresponding to the ribs 2 at two adjacent side edges, the tongues (not shown) being at the two other side edges, and the ribs 11 have 70 the grooves 12 corresponding to the grooves 3 for receiving tongues of the adjacent slab. The slab is otherwise the same as shown in Fig. 3, having the grouting openings 5, and is laid in the same manner.

The openings 5, in practice, will be about 75 an inch and a half in diameter and spaced about two feet apart, and the grouting poured into these openings will fill in the space between the under side of the slabs 80 and the surface of the ground, giving a bearing at frequent intervals so as to maintain the level at which the slabs are laid, and when the slabs are laid on an incline the grouting will prevent creeping.

The engagement of the tongue and groove 85 prevents the slabs getting out of alinement at the joints, and in case of general settlement relining is permitted.

The improved slab may be made from 90 Portland cement, mortar, or concrete, which may be mixed with fine gravel, broken rock or the like, and reinforced with wire mesh, the dimensions of the slab being of a size to facilitate handling.

I claim:

1. A pavement composed of slabs molded of plastic material capable of hardening, each slab having at one edge a depending rib grooved on its outer face, and at the 100 other an outwardly extending tongue adapted to engage the groove of an adjacent slab, each slab having openings near its edges and intermediate the said edges for permitting grouting to be poured after the slabs are 105 laid, the tongues being rounded and the grooves shaped to fit the tongues.

2. A pavement composed of slabs molded of plastic material capable of hardening, each slab having at one edge a depending 110 rib grooved on its outer face, and at the other an outwardly extending tongue adapt-

ed to engage the groove of an adjacent slab, each slab having openings near its edges and intermediate the said edges for permitting grouting to be poured after the slabs 5 are laid.

3. A pavement composed of slabs molded of plastic material capable of hardening, the slabs having at their side edges interlocking tongues and grooves, and a series of 10 transverse openings for permitting grouting to be poured through the openings to form supports for the slabs, said tongue and 15 groove connection depending below the level of the under surface of the slabs and said slabs having their edges abutting to above the tongue and groove connection.

4. A pavement composed of slabs molded

of plastic material capable of hardening, the slabs having at their side edges interlocking tongues and grooves, and a series of 20 transverse openings for permitting grouting to be poured through the openings to form supports for the slabs.

5. The process of constructing a pavement which comprises providing reformed slabs 25 having holes therein, setting stakes with their upper ends at a regulated height, supporting said slabs upon said stakes with their edges in contact and pouring grout through said holes so that said grout will 30 spread beneath said slabs to form permanent supports for the pavement and also fill said openings.

WARREN JOHNSON.
